UNITED STATES PATENT OFFICE.

GIDEON ANDERSON, OF NEW YORK, N. Y., ASSIGNOR TO THE WEST GRAVITISER CORPORATION, OF NEW YORK, N. Y., A CORPORATION OF NEW YORK.

ТИЛТИНГ ТАБЛ.

Application filed July 28, 1929. Serial No. 399,623.

To all whom it may concern:

Be it known that I, GIDEON ANDERSON, a subject of the King of Sweden, and a resident of New York, in the county of Bronx and State of New York, have invented certain new and useful Improvements in Tilting Tables, of which the following is a specification.

My invention relates to tilting tables of the type shown in Letters Patent No. 1,331,041, granted to me Feb. 17, 1920, and which, while susceptible of various uses, are primarily intended for use as a support upon which a person may rest at certain angles of inclination for the purpose of exercising within limits the vascular system, for curative or health purposes; this being accomplished by having the table upon which the patient rests tilted at a series of prescribed angles below the horizontal.

A table of this type comprises a supporting frame, a table upon which the patient or other user rests pivotally mounted on said frame for tilting movement, and a table tilting mechanism adapted to be operated either by the patient on the table or by an attendant, for tilting the table to the desired angle of inclination.

The table tilting mechanism comprises connections between the supporting frame and the table which are subjected to considerable strain under the loads carried by the table, and in case of any overload on the table, such connections and associated parts are liable to breakage or other injury. To prevent this has been one of the objects of my present invention, and which object I attain by providing a connection between certain parts of the tilting mechanism that will permit of a yielding of the parts when subjected to excessive strains.

Another feature of the invention is the provision of means for rendering the operation of the tilting mechanism more noiseless than heretofore. This tilting mechanism embodies a pawl and ratchet, the noise of which, produced by the sliding of the pawl over the ratchet teeth, is objectionable to highly nervous persons. To avoid this noise and thereby render the use of the device more desirable, I have provided a means for preventing engagement of the pawl with the ratchet teeth on the return or reverse movement of the pawl.

Another feature of the present invention

relates to means for indicating the degree of inclination to the horizontal at which the table is tilted. In the use of the table, certain angles of inclination are prescribed for the use of the particular patient, and it is therefore desirable that some means should be provided whereby the user or the attendant may readily determine when the table is tilted at the prescribed angles. To do this, I have provided an indicating mechanism comprising a striker that is automatically operated by the movement of the table to indicate the varying degrees of inclination of the table as it is moved either from or towards the horizontal.

Referring now to the drawings forming part of this specification—

Fig. 1 is a side elevation of a tilting table embodying my invention, opened up and ready for use.

Fig. 2 is a similar view showing the same closed.

Fig. 3 is an end view looking from the left in Fig. 1.

Fig. 4 is an enlarged sectional detail of the table tilting mechanism, with the operating lever in raised position.

Fig. 5 is an enlarged detail, in top plan, showing both the table tilting mechanism and the striker indicator mechanism.

Fig. 6 is a side elevation of the same, with the tilting mechanism in section on the line 6—6 of Fig. 4.

Fig. 7 is a plan view, partly in section, of the indicator mechanism, the same corresponding with the left-hand end of Fig. 5 but on a larger scale.

Fig. 8 is a section on the line 8—8 of Fig. 7.

Fig. 9 is an enlarged view taken on the line 9—9 of Fig. 4, showing certain parts of the tilting mechanism which are housed within the operating lever thereof.

Fig. 10 is a detail of the upper end of the operating lever, partly broken away, showing the adjustment for adapting the lever to either raise or lower the table.

Figs. 11 and 12 are edge and side views, respectively, of a device for rendering noiseless the pawl and ratchet of the tilting mechanism.

Fig. 13 is a detail view to be hereinafter referred to.

Similar reference characters indicate like parts in the several figures of the drawings.

The table or body support and the frame on which it is pivotally mounted are both collapsible for adjustment from the open operative position shown in Figs. 1 and 3, to the closed inoperative position shown in Fig. 2.

The supporting frame comprises a pair of parallel top rails 2, 2, and a pair of parallel base rails 3, 3, the top rails being connected with the base rails by a plurality of pairs of diagonally arranged cross-braces 4, 4, which are hinged at their ends to the rails, as at 5, and pivoted together at their points of intersection, as at 6. Such connection of the cross-braces with the opposite side rails permits of the latter being brought or folded together laterally. In order now that the upper rails may be folded down against the lower rails and the whole supporting frame be caused to assume the small compact form shown in Fig. 2, the hinge members between the cross-braces and the rails are connected to the latter by pivots, such as 7, which are arranged transversely of the rails to permit of the cross-braces swinging in a direction longitudinally of the rails, as will be understood by reference to Fig. 2.

As a means for controlling the opening and closing of this collapsible supporting frame, I have connected the upper and lower rails at each side of the frame by a plurality of pivoted links 8 which are somewhat longer than the distance between the upper and lower rails when the frame is in open position, as shown in Fig. 1, whereby, upon the closing or collapsing of the frame, the upper rails will be caused to move longitudinally a sufficient distance to draw the upper and lower ends of the cross-braces, and thereby the connected rails, together laterally. In this way, downward pressure upon either one or both of the top rails will cause a collapsing of the frame both vertically and laterally, while an upward pulling of either one or both of said top rails will likewise cause a similar opening up of the frame in both directions.

Suitably mounted upon this collapsible frame for tilting movement is the table proper, adapted to support the patient, said table, as here shown, comprising two side rails 11, 11, carrying an intermediate strip of canvas or like material 12. This table may be pivotally mounted on the supporting frame in any suitable manner. In the present case, the top rails of the supporting frame are each provided at one end thereof with a pair of spaced bracket plates 14, 14, carrying a pivot 15, upon which the opposite side rails 11 of the table are fulcrumed.

It will be understood that by reason of the connection of the side rails of the table with the side rails of the supporting frame, the table will be opened and collapsed with the opening and collapsing of the frame,

this being permitted so far as the body support 12 is concerned by reason of its flexibility. As a means for holding the table in its open position, the side rails of the same are connected at their ends by hinged cross-bars 17.

The mechanism for tilting the table comprises a segmental rack 20, rigidly attached to the table by suitable fastening means such as the bolt 21, and a co-operating pinion 22 carried by a shaft 23 journaled to one of the upper rails of the supporting frame; the rotation of said pinion acting through the rack 20 causing the table to rock on its fulcrum support 15. As here shown, the shaft 23 is journaled in a bearing sleeve 24, which extends through transverse openings in the frame rail 2 and the bracket plates 14, 14, at opposite sides thereof, and is clamped in connection with the frame by means of a head 25 at one end thereof engaging one bracket plate and a nut 26 threaded on its other end for clamping engagement with the opposite bracket plate, as clearly shown in Fig. 4.

The pinion 22, in accordance with the present invention, is connected with the shaft 23 in a manner which will assure its being operated by the shaft to raise and lower the table under normal loads thereon, but which will permit of its turning relatively to the shaft under any overload on the table and thereby avoid possibility of damage to the apparatus through undue strains or breakage of the parts. Such connections between the pinion and shaft is a frictional one and is obtained by the following means: The pinion is loose on the shaft and has secured to opposite sides thereof, by fastening pins 29, two steel discs 28, 28, which are also loose on the shaft. Between these pinion discs 28, 28, and a pair of discs 30, 30', keyed to the shaft, are friction washers 32, of brass or like material, two of these washers with an interposed spacing washer 31 being shown at the outer side of the pinion, and one washer being shown at the opposite or inner side of the pinion. By causing a frictional engagement between these discs 30 and 30' keyed on the shaft 23, and the discs 28, 28, fastened to the pinion 22, it will be understood that rotation of the shaft will be imparted to the pinion. Such a frictional engagement may be effected by any suitable clamping means, the means here shown for the purpose comprising a shoulder 36 on the shaft against which the outer disc 30 bears, and a co-operating compound adjusting nut 37 threaded onto the outer end of the shaft and acting through a spring washer 38 (and certain intermediate braking members to be hereinafter referred to) against the outer disc 30'.

Now in order to hold the shaft against rotation under the weight of the table and its

load, I have provided a braking means comprising a stationary disc 34 surrounding the shaft at a point between the disc 30' on one side and an end disc 39 on the other side, 5 both being keyed on the shaft, and friction washers 34', 34', interposed between said discs as shown. By causing sufficient friction between the stationary disc 34—here shown as carried by a bracket arm 35 attached to the frame—and the discs 30' and 39 keyed on the shaft, it will be understood that the shaft will be held against turning movement except that produced by its operating means, hereinafter described. The 15 means here shown for effecting the desired friction between the members of the braking means comprises the adjusting nut 37, which, in the arrangement of parts shown, is operative to effect the proper adjustment of 20 both the shaft braking means just described and also the frictional connection of the pinion with the shaft.

Pivottally mounted on the outer end of the shaft 23, or that end opposite the pinion carrying end, is a tubular operating lever 40 having a pawl and ratchet connection with the shaft for imparting rotary movement thereto, the pawl, indicated at 41, being carried by said operating lever, and the 25 ratchet, indicated at 42, being keyed on the shaft and detachably held thereon by a nut 43, threaded on the outer end of the shaft and clamping the ratchet against a shoulder thereon, as clearly shown in Fig. 4.

30 The pawl 41 is a double one—being pivoted at its center on a pin 44—in order that it may be caused to engage at either end with the ratchet teeth according to the direction of rotation to be imparted to the shaft 23 and attached pinion 22 for controlling the raising and lowering movements of the table.

35 As a means for controlling the action of the pawl to cause either one or the other of its ends to engage the ratchet teeth, according to whether the table is to be raised or lowered, I mount an elbow lever 45 on a pivot 46 within the tubular lever 40 for engagement, through a projecting spring-pressed ball 47 at its lower end, with the upper edge of the pawl 41 at either side of its center; this device being operative to yieldingly hold the particular end of the pawl 50 with which it engages in operative relation with the ratchet 42, as will be clear by reference to Fig. 9. For shifting this elbow lever to either end of the pawl, it is engaged at one side by a spring 48 supported on a pin 49 within the tubular lever 40, and at 55 its opposite side by the lower end of a rod 50 which is supported for longitudinal sliding movement in suitable bearings 51 in the lever 40 with its upper end in engagement with a cam lever 52, which latter is pivoted at 53 in the upper end of the lever 40 and

provided with a handle portion 54 projecting outwardly through a slot 55 in the lever in a convenient position to be manipulated by the patient on the table. By turning this cam lever in any one direction, it will act 70 through the rod 50 to hold the lever 45 in operative relation with one end of the pawl, and by swinging said cam lever in the opposite direction, it will permit the lever 45 to be shifted by the spring 48 to a position of 75 operative relation with the opposite end of said pawl.

In order to assure the operating lever 40 being held in raised position where it may be conveniently grasped by the operator, means 80 are provided for maintaining a frictional connection between the same and the shaft on which it is mounted. This means comprises two fibre washers, 60 and 61, seated within annular depressions in the opposite 85 sides of the ratchet 42 and acting against adjacent parts of the lever under the influence of a series of coiled springs 62 which are seated within transverse openings 63 in the ratchet, as shown in Figs. 4 and 9. One 90 of these washers, that indicated at 60, bears directly against one inner wall of the lever, while the other washer, indicated at 61, acts against the opposite inner wall of the lever through an interposed disc 65 to be hereinafter referred to. With this frictional connection between the lever and the ratchet—the latter being keyed to the shaft—the lever will be maintained in its upright position 95 when released by the operator, although of course capable of being moved downward and out of the way when so desired.

In order to obviate the clicking noise incident to the use of a pawl and ratchet, which noise is objectionable to highly nervous persons, I have provided a so-called "silencer." This comprises the disc 65, which is interposed between the washer 61 and the adjacent wall of the operating lever 40 and provided at one side thereof with a lug 66 engaging the lever within an opening 67 therein, whereby the disc will be caused to turn with said lever, and at its opposite side provided with two guard-lips 68, 68, positioned adjacent the opposite ends 110 of the pawl 41 for preventing engagement of the same with the ratchet upon the backward or reverse stroke of the lever. Referring to Fig. 9, it will be noted that one end 115 of the pawl is in engagement with the ratchet and that the lug 66 on the disc 65 is in contact with one wall of the opening 67 in the lever 40. The several parts in these positions are ready for a forward or operative stroke of the lever. As this stroke 120 takes place, the parts will maintain the same relative positions, the engagement of the lug 66 on the disc 65 with the wall of the opening in the lever causing said disc to be rotated forwardly with the lever. 125

Now upon the reverse stroke of the lever—bearing in mind the fact that the friction between the disc 65 and the ratchet with its fibre washer 60 is greater than that between 5 the disc and the lever whereby the disc will be held to the ratchet and so permit movement of the lever relative thereto—the pawl will first ride up onto the adjacent ratchet tooth and also onto the adjacent guard-lip, 10 by which latter it is prevented from dropping into the space between the ratchet teeth. During such backward movement of the lever to bring the pawl onto the guard-lip, it will have advanced sufficiently 15 to bring the opposite wall of its opening 67 into engagement with the disc lug 66, as shown in Fig. 13, after which the parts will move together with the pawl held from contact with the ratchet teeth by the 20 engaging guard-lip 68. Now upon the succeeding forward stroke of the lever, the disc 65 will be held stationary until the pawl has been moved forward of the supporting guard-lip and into engagement with 25 the next ratchet tooth, at which time the rear wall of the lever opening 67 will have advanced into engagement with the disc lug 66, as shown in Fig. 9, after which the 30 parts will move together as hereinbefore described. It will of course be understood that both guard-lips 68 co-operate with the adjacent ends of the pawl 41 in like manner.

The means for indicating to the patient 35 the angle of inclination to the horizontal at which the table is tilted, comprises a pair of striking devices, one being operative on the downward movement of the table and the other on the upward movement of the 40 table, and a single operating mechanism common to both said devices. The striking devices comprise two oppositely located sound plates 70, 70, mounted on one of the side rails 11 of the table, and co-operating 45 strikers 71, 71, the said sound plates being here shown as laterally projecting flanges of a supporting plate 72 bolted to one side of the said rail, and the strikers being each pivotally mounted on a short shaft 73 which 50 is carried by an adjustable support 74 pivoted at 75 to an outer bearing plate 76, also bolted to the rail 11, as shown in Figs. 5, 6, 7 and 8. A spring 77 connecting with rear extensions of the strikers serves to normally hold the latter in contact with the 55 sound plates, and to snap them into striking contact therewith when drawn backward and released. For rocking the strikers on the shaft 73 is a T-lever 78 mounted 60 on said shaft 73 with two arms arranged for engagement with pins 79, 79, on the opposite strikers, as shown by dotted lines in Fig. 8, and its third arm having a pin 80 adapted to be engaged by pins 81 on an 65 actuating wheel 82. Rotation of this wheel

82 in one direction, as effected by the lowering of the table through means to be hereinafter described, causes each successive pin thereon to engage the pin 80 on the lever 78 and rock the lever and one of the 70 engaged strikers in a direction to withdraw the striker from contact with its co-operating sound plate, and, after said pin of the wheel 82 in its continued advance releases 75 the pin 80, the striker will be snapped back 75 into striking engagement with the sound plate under the action of the spring 77; this return of the striker also operating to return the lever 78 to its normal position 80 shown in Fig. 8. Rotation of the wheel 82 in the opposite direction, as effected by the raising of the table, will act through the lever 78 to cause a corresponding operation 85 of the opposite striker, as will be clear by reference to Fig. 8.

The means here shown for operating the strikers in the way described, comprises a stationary gear 85 mounted on the table pivot 15 and meshing with a pinion 86 on a shaft 87 carried by the table rail 11, which shaft also carries a gear 88 meshing with a pinion 89 on the shaft 90 which carries the striker actuating wheel 82. With this means, it will be understood that the actuating wheel 82 will be automatically rotated in one direction upon the lowering 95 of the table and in the opposite direction upon the raising of the table.

As shown in Fig. 8, the wheel 82 is provided with one series of concentrically arranged pins 81 so spaced as to effect a striking operation at each change of a single degree in the angle of inclination to the horizontal at which the table is tilted. It 100 will be obvious, however, that these striking pins may be variously arranged to indicate different degrees of movement as may be desired. For instance, the wheel is shown as provided with two pins 91, 91, outside of the circle of the series 81, which are arranged 105 to indicate a movement of five degrees. In order to adjust the pin 80 on the lever 78 for co-operation with either one or the other of the two sets of actuator pins 81 and 91, the pivoted support 74 for the shaft 73 and parts mounted thereon, is held by a spring 92 with a washer 93 on said shaft in contact with an adjustable eccentric pin 94 (see Figs. 7 and 8), whereby, upon the proper adjustment of 110 said eccentric pin, the support 74 may be shifted to adjust the lever 78 and its pin 80 with respect to the pins on the actuator wheel 82. By shifting the support 74 to its extreme rear or left-hand position, the pin 80 will be moved entirely out of the path of the actuator pins on the wheel 82 and so render the indicator or striking mechanism 115 wholly inoperative when so desired.

The adjusting eccentric pin 94 may be 120 supported and operated in any suitable or 125

desired way. As here shown (see Fig. 7) it is carried by a head 95 rotatably mounted in a socket 96 in the rail 11, and engaged by one end of a shank 97, which latter at its 5 outer end connects with an operating button 98 rotatably mounted in a bearing plate 99 at the face side of the rail 11. A spring-pressed ball 100 carried by the button and engaging the face of the bearing plate 99 10 within suitably spaced depressions 101 therein, serves to yieldingly hold the button and the associated eccentric pin 94 in adjusted position.

A coiled spring 102 interposed between 15 the inner side of the button 98 and the eccentric head 95 operates to hold the latter to its seat in the socket 96.

What I claim is:

1. In a device of the character described, 20 a supporting frame; a table pivotally mounted on said frame; and table tilting mechanism comprising a shaft, operative connections between said shaft and the table, a ratchet wheel on said shaft, a pivoted 25 operating lever having a pawl for engagement with said ratchet wheel, and means for preventing engagement of the pawl with the ratchet teeth during the reverse stroke of the operating lever.

2. In a device of the character described, 30 a supporting frame; a table pivotally mounted on said frame; and table tilting mechanism comprising a shaft, operative connections between said shaft and the table, a ratchet wheel on said shaft, a pivoted 35 operating lever having a pawl for engagement with said ratchet wheel, and means movable with the pawl for preventing engagement of said pawl with the ratchet 40 teeth during the reverse stroke of the operating lever.

3. In a device of the character described, 45 a supporting frame; a table pivotally mounted on said frame; and table tilting mechanism comprising a shaft, operative connections between said shaft and the table, a ratchet wheel on said shaft, a pivoted 50 operating lever having a pawl for engagement with said ratchet wheel, and a guard 55 movable with the pawl for preventing engagement of said pawl with the ratchet teeth during the reverse stroke of the operating lever, said guard having connection with said lever to be moved thereby with the 60 pawl.

4. In a device of the character described, 65 a supporting frame; a table pivotally mounted on said frame; and table tilting mechanism comprising a shaft, operative connections between said shaft and the table, a ratchet wheel on said shaft, a pivoted 70 operating lever having a pawl for engagement with said ratchet wheel, and a guard movable with the pawl for preventing engagement of said pawl with the ratchet 75 teeth during the reverse stroke of the lever and having movement relative to said pawl to permit the latter engaging the ratchet teeth on the forward stroke of the lever.

5. In a device of the character described, 80 a supporting frame; a table pivotally mounted on said frame; and table tilting mechanism comprising a shaft, operative connections between said shaft and the table, a ratchet wheel on said shaft, a pivoted 85 operating lever having a pawl for engagement with said ratchet wheel, a guard for preventing engagement of said pawl with the ratchet teeth during the reverse stroke of the pawl, and controlling means for said guard operative to hold the same stationary 90 relatively to the ratchet upon the initial movement of the latter at both its reverse and forward strokes, whereby the pawl will be caused to engage the guard on its reverse stroke and to disengage therefrom on its forward stroke, for the purpose set forth.

6. In a device of the character described, 95 a supporting frame; a table pivotally mounted on said frame; and table tilting mechanism comprising a shaft, operative connections between said shaft and the table, a ratchet wheel on said shaft, a pivoted 100 operating lever having a pawl for engagement with said ratchet wheel, a guard for preventing engagement of said pawl with the ratchet teeth during the reverse stroke of the pawl and being loosely connected with the lever to be moved thereby, and controlling means for said guard, including a friction brake, operative to hold the same stationary relatively to the ratchet upon the initial movement of the latter at both its reverse and forward strokes, whereby the pawl will be caused to engage the 105 guard on its reverse stroke and to disengage therefrom on its forward stroke, for the purpose set forth.

7. In a device of the character described, 110 a supporting frame, a table for the support of a patient pivotally mounted on said frame, mechanism for tilting said table and holding it in adjusted position, and sound-producing striking means for indicating the degree of inclination to the horizontal at 115 which the table is tilted.

8. In a device of the character described, 120 a supporting frame, a table for the support of a patient pivotally mounted on said frame, mechanism for tilting said table and holding it in adjusted position, and sound-producing striking means operated by the movement of the table for indicating the degree of inclination to the horizontal at which the table is tilted.

9. In a device of the character described, 125 a supporting frame, a table for the support of a patient pivotally mounted on said frame, mechanism for tilting said table and holding it in adjusted position, and sound- 130

producing striking means operated by the table on both its lowering and raising movements for indicating the degree of inclination to the horizontal at which the table is 5 tilted.

10. In a device of the character described, a supporting frame, a table pivotally mounted on said frame, and duplex striking means for indicating the degree of inclination to the horizontal at which the table is tilted, one set being operated by the lowering movement of the table and the other by the raising movement of the table.

11. In a device of the character described, 15 a supporting frame, a table pivotally mounted on said frame, and striking means for indicating the degree of inclination to the horizontal at which the table is tilted, said means comprising a striker mounted 20 on the table, an actuator mounted on the frame, and connections between said actuator and the striker operative to actuate the latter upon the tilting of the table and at predetermined points in the movement of the latter.

12. In a device of the character described, a supporting frame, a table pivotally mounted on said frame, striking means associated with the frame and table and operated 30 by movement of the latter to indicate its degree of inclination to the horizontal, and means for regulating the action of the striking means.

13. In a device of the character described, 35 a supporting frame, a table pivotally mounted on said frame, striking means associated with the frame and table and operated by the movement of the latter to indicate its degree of inclination to the horizontal, and means for rendering the striking means 40 inoperative.

14. In a device of the character described, a supporting frame, a table pivotally

mounted on said frame, a striker for indicating the degree of inclination to the horizontal at which the table is tilted, striker actuating means operated by the movement of the table, an adjustable support for the striker, and means for shifting such support to either regulate the action of the striker 50 or else render it inoperative.

15. In a device of the character described, a supporting frame, a table pivotally mounted on said frame, a striker mounted on the table for indicating the degree of 55 inclination to the horizontal at which said table is tilted, and striker actuating means comprising a train of gearing associated with both the frame and table and operated by the movement of the latter.

16. In a device of the character described, a supporting frame, a table pivotally mounted on said frame, table tilting mechanism comprising an operating shaft and a 60 rack and pinion connection between said shaft and the table, the pinion being yieldably associated with the shaft, and braking means for holding the shaft and its associated parts in adjusted position.

17. In a device of the character described, 70 a supporting frame, a table pivotally mounted on said frame, table tilting mechanism comprising an operating shaft and a rack and pinion connection between said shaft and the table, means for frictionally 75 holding the pinion in operative connection with the shaft, braking means for holding the shaft and its associated parts in adjusted position, and means for adjusting the action of both the said frictional pinion 80 holding means and the braking means.

Signed at New York, in the county of New York, and State of New York, this 24th day of May, A. D. 1920.

GIDEON ANDERSON.
